UNITED STATES PATENT OFFICE.

DAVID J. FARMER, OF PENN YAN, ASSIGNOR OF ONE-HALF TO R. NELSON GERE, OF SYRACUSE, NEW YORK.

HORSESHOE-MACHINE.

SPECIFICATION forming part of Letters Patent No. 331,623, dated December 1, 1885.

Application filed April 23, 1884. Serial No. 128,900. (No model.)

To all whom it may concern:

Be it known that I, DAVID J. FARMER, of Penn Yan, in the county of Yates, in the State of New York, have invented new and useful Improvements in Horseshoe-Machines, of which the following, taken in connection with the accompanying drawings, is a full, clear, and exact description.

This invention relates to a machine designed to manufacture horseshoes and mule-shoes complete from the bar, and has more particularly reference to the machine for which Letters Patent No. 243,536 were granted to D. J. Farmer and S. Farmer on the 28th day of June, 1881.

The object of this invention is to make said machine more durable and more efficient in its operation; and to that end the invention consists in the improved construction and combination of the constituent parts of the machine, as hereinafter fully described, and set forth in the claims.

In the annexed drawings, Figure 1 is a plan view of my improved horseshoe-machine and its feed mechanism. Fig. 2 is an end view of the same, the mechanism which actuates the shoe-bending rollers being omitted to better illustrate some of the important features of my invention. Figs. 3 and 4 are vertical sections taken respectively on lines xx and yy , Fig. 2. Fig. 5 is an elevation taken at the side of the machine, showing the connection of the main shaft with the oscillating shaft of the arm which carries the die and former for bending the shoe. Fig. 6 is a detached plan view taken immediately above the feed passage of the machine with the removable presser taken off the slide to show the adjustable feature of the bar-severing knives and also the device for bending the bar around the former. Fig. 7 is a vertical transverse section showing in detail the construction and combination of the devices for simultaneously creasing and swaging the bar from which the shoe is to be formed. Fig. 8 comprises a front view, end view, plan view, and transverse section of the creaser and its support. Fig. 9 is a vertical transverse section of the slide with the guide-groove and the presser, by which latter the bar is pressed against the creaser, and showing the removable lining of the

guide-groove and the spring which retracts the slide. Fig. 10 is a detached face view of the suspended swage. Fig. 11 is an edge view of a bar from which the shoe is to be formed, 55 and illustrating the effects of the swage and creaser. Fig. 12 is a face view of the oscillating former-arm, showing the compressing-jaws thereof in their normal position. Fig. 13 is a detail view illustrating the operation of the aforesaid jaws in conjunction with the compressing-roller. Fig. 14 is a longitudinal section of the free end of the former-arm, showing the attachment of the shoe-compressing jaws; and Fig. 15 is a horizontal section on line zz in Fig. 3, and Fig. 16 is a longitudinal section of the oscillatory arm which carries the die and former.

Similar letters of reference indicate corresponding parts.

A represents the supporting-frame of the machine. It consists, essentially, of a stout bed or base from which rise two rigid walls. In suitable bearings on said walls are mounted the rotary main shaft B and a rock-shaft, 75 F, extended across the frame, the main shaft being provided on one of its ends with a crank-wheel, G, which is connected by a rod, H, with an arm, I, on the rock-shaft, and thus transmits the requisite motion to the latter. 80 To the rock-shaft is attached the oscillatory arm K, which carries on its free end the die L and former M, around which the horseshoe-blank is bent in the manner hereinafter explained, said former being seated in a longitudinal cavity in the die and backed by a spring which yieldingly holds the former to 85 protrude at the face of the arm K in the usual and well-known manner and not necessary to be here illustrated.

Across the path of the oscillatory arm K, and nearly or quite in range with the face thereof, is a channel, a' , formed by a plate, b, extended across the upper part of the frame A, and by a rabbeted plate, b' , secured to the 95 top of the plate b, the upper plate having a notch, c, to allow the former M to pass through it in the oscillation of the arm K. The lower plate has an excision, c' , of such a length as to compel the bar introduced in the channel a' 100 to be bent part way around the former M in its passage through said excision. The bend-

7c

100

ing of the aforesaid bar is completed by the same mechanism as described and shown in the patent of D. J. Farmer and S. Farmer, No. 243,536, hereinbefore referred to, said mechanism consisting of rollers 8 8, mounted on horizontal slides 9 9, which are arranged at opposite sides of the path of the former M, and are moved toward and from the same by levers 10 10, the outer ends of which are drawn together by a spring to retract the rollers, and are forced apart by a wedge, 11, on the end of an arm, 12, fastened to a shaft, 13, and turned by a cam, 14, on the main shaft, acting on an arm, 15, on the shaft 13 at the proper period, and 15 to the necessary extent to cause the rollers 8 8 to be forcibly pressed against the partially-bent blank, and by following around the outer edge thereof and forcing it against the former to complete the bending of the blank as it is 20 carried down between said rollers by the former.

Before the bar is subjected to the aforesaid bending process it is subjected to a swaging and creasing process by the following instrumentalities: On the end of the plate b, at the feed side of the machine, is arranged an adjustable creaser, C, consisting of a horizontal plate presenting a beveled edge toward the feed-passage or guide-groove a of the machine, which plate rests in a holder or sustaining-shoe, f, having flanges f' extended around three sides thereof, and overhanging the top to embrace the creaser C, and a cover, f'', placed upon the creaser, as shown in Fig. 8 of the drawings. The holder f rests with its front portion on an elevation near the edge of the plate b, forming a rocker-bearing for the holder f. The rear portion of the said holder is supported by set-screws e e, extended vertically 35 through the holder, and bearing with their lower protruding ends on the plate b. The set-screws work in screw-threaded eyes in the holder, and by turning them the rear portion of the holder f is raised or lowered, as may be 40 required to bring the creaser C in proper position over the guide-groove a to crease the bar from which the shoe is to be formed.

By means of a dog, h, removably attached at one end to either the frame A or a portion 50 of the plate b back of the holder f, and bearing with its opposite end or free end on top of the cover f'', the creaser is firmly held in its sustaining-shoe f, and the latter is confined to its bearings on the plate b.

Opposite the creaser C and facing the same is a slide, S, mounted on the wall of the frame A, which slide carries a plate, E, provided with a grooved overhanging portion, the groove a of which constitutes the feed-passage where- 55 in to pass to the machine the bar from which the shoe is to be formed. Said groove a is adapted to be brought in range with the channel a', hereinbefore described, so that an uninterrupted passage to the oscillatory former 60 is obtained.

On the plate E is hinged the presser D, the free end of which is provided with an over-

hanging face, D', occupying the side of the groove a opposite the creaser C and serving to press against the latter the bar to be creased 70 preparatory to bending it into shoe shape, as hereinafter described.

The object of hinging the presser is to render it readily removable from the groove a whenever it becomes necessary for the operator to obtain access to said groove or in case the bar is to be fed to the machine without creasing the bar. The position of the presser when removed as aforesaid is illustrated by dotted lines in Fig. 9 of the drawings. 80

In order to admit of repairing or renewing the face D' of the presser when required, I fasten said face on the hinged part D by removable bolts or other suitable detachable fastenings, which allow the face D' to be removed from said part D. The slide S, with its aforesaid appurtenances, receives a quick reciprocating motion by means of vertical levers P P, pivoted on opposite sides of the frame A by the rock-shaft passing loosely 90 through them. Said levers are provided above their fulcrums with sockets, in which rest the ends of push-bars or knuckles k k, which are pivoted at their opposite ends on the slide S, and serve to push said slide toward the creaser 95 by the movement of the levers P P in one direction.

The slide S is retracted during the movement of the levers in the opposite direction by the following instrumentalities: Horizontally 100 through a socket in the back of the slide S passes a rod, l, which is provided with a head in said socket, and between the head of the rod and end of the socket is interposed a spiral spring, m. The opposite end of the rod l is screw-threaded and screwed into a socket in the wall of the frame A, rising between the levers P P, as illustrated in Figs. 1 and 9 of the drawings. The spring m becomes compressed by the movement of the slide S 110 toward the creaser, and the resistance of said spring serves to retract the slide so soon as the latter is relieved of the pressure transmitted to it by the knuckles k k in the manner before stated. 115

To the main shaft B are attached cams Q Q, having an eccentric contour terminating abruptly, as at g, Fig. 4 of the drawings. These cams engage the lower end of the levers P P, and impart a quick and positive oscillatory movement to the same. Back of the lower ends of the two levers are elbow-levers R R, one arm of each of which rests on a stout spring, n, and the other arms are connected with the lever P by push-bars n' n'. These elbow-levers 120 serve to quickly throw the lower ends of the levers P P forward after the release of the latter from the cam Q. The described movement is essential in order to accelerate the creasing process, and thus prevent as much as 125 possible the heating of the creaser C, which heating is one of the defects of the machine covered by Letters Patent No. 243,536, hereinbefore referred to. Over the creaser C is a 130

rock-shaft, T, mounted on portions of the frame A, rising above the creaser, and from said rock-shaft project two firmly-attached jaws, T' T', from which is suspended the swage-carrying arm U, the connection of said arm with the jaws T' being such as to allow the said arm to swing and follow the slide S in its movement, and thus maintain its hold on the shoe-blank while subjected to the action of the creaser, as illustrated in Fig. 7 of the drawings. The swage U' is secured to the arm U in such a manner as to allow it to be detached for repairs or renewal, or for exchanging it with other swage-irons of different forms and dimensions, as may be required for the different sizes of shoes to be formed. The swage-iron normally stands directly over the feed-passage a, and receives a downward pressure by a lever, V, fastened to the end of the rock-shaft, and having its free end lying against and actuated by a cam, V', secured to the main shaft B. The cams Q and V' are arranged in such relation to each other as to synchronously actuate the slide S and rock-shaft T. The bar from which the shoe is to be formed being introduced in the groove or feed-channel a, and brought in proper position between the creaser C and slide S, is pressed against the creaser by the presser D D' on the slide S, and simultaneously receives the impact of the swage U', the pressure of which latter resists the vertical distention of the bar incident to the action of the creaser, and at the same time imparts to the bar the contour illustrated in Fig. 11 of the drawings, whereby the ends of the bar receive a lateral distention, which produces the requisite increased thickness at the heels of the shoe. After the aforesaid creasing and swaging has been effected, the slide S, with its presser D D', and the swage U' recede immediately from the bar. In the latter movement the slide S draws the bar away from the creaser by the so-called strippers o and o' connected respectively to the inner end of the slide and to the outer end of the portion of the plate E, which is provided with the groove or feed-passage a. Said strippers engage the edge of the heated bar adjacent to the creaser, and in addition to their aforesaid function also serve to guide one side of the bar in its movement on the feed-passage.

The form and operation of the inner stripper are illustrated in a separate view under Fig. 6 of the drawings.

In order to preserve the plate E, I apply to the part thereof which contains the feed-passage a a steel lining, a², fitted removably in a dovetail countersink in the passage a, as shown in Fig. 9 of the drawings. By renewing the lining a² when worn, the feed-passage is maintained in proper condition without the necessity of renewing the entire plate E. After the before-described creasing and swaging process the bar from which the shoe is to be formed is advanced by the feed mechanism hereinafter described, which carries the creased

and swaged portion of the bar in front of the oscillating former-arm K, the position of the bar being determined by a gage, r, which is 70 adjustably attached to the plate b, and adapted to be set a greater or less distance from the center of the portion of said plate traversed by the former M of the oscillatory arm K, according to the length of the bar required to 75 form the shoe. The bar is carried to the gage r while the creasing and swaging mechanism are at rest, and in the next movement of said mechanism the bar is severed by two knives, p p', one of which is attached to the inner end 80 of the plate E, carried by the slide S, and the other knife, p', is attached to the plate b, hereinbefore described, said knives standing at right angles to the feed-passage a, and being caused to sever the iron by the approach of 85 the slide S toward the creaser C in the operation of creasing and swaging the portion of the bar adjacent to that which is carried in front of the arm K. The aforesaid knives I make adjustable in their position in relation 90 to their distance from the gage r by fitting the plate E, which carries the knife p, loosely on the slide S, and providing said plate with a slot, s, through which its attaching-screw passes. By loosening said screw the plate E 95 can be shifted to carry the knife farther from or nearer to the gage or stop r, the knife being subsequently retained in position by tightening the attaching-screw of the plate E. The other knife, p', is adjusted to conform to the 100 position of the knife p by interposing a lining or compensating-block between the knife p' and the face of the plate b, to which it is attached. With the suspended swage-carrying plate U, I connect a lever, V', pivoted 105 to a suitable support back of the said plate. By means of this lever I am enabled to draw the swage rearward and away from its position over the feed-passage a, and thus prevent the swage from operating on the bar 110 when desired, and also clear the passage of all obstructions, so that access can be had thereto when required.

The former M and die L of the oscillating arm K are similar to those shown in the patent of David L. Farmer and Samuel Farmer, hereinbefore referred to; but I now employ, in combination with the aforesaid parts, two jaws, N N, one on each side of the die L. These jaws are connected with the former-arm K in 115 such a manner as to allow them to yield endwise and laterally, and are normally held to project at the face of the die L. The connection of said parts is here represented to consist in pivoting the lower portion of the jaws 120 to the wide portion of the die L with the face of the hinged portion of the jaw flush with the face of the die, the upper portion of the jaws being held in a protruding position by a spring, u, pressing against the inner end of 125 the jaw, as illustrated in Fig. 14 of the drawings, the jaw having a lateral play on its pivotal pin.

On the outside of the jaws N N are plates

O O, hinged or pivoted, respectively, to opposite sides of the arm K in such a manner as to allow the free ends of said plates to yield laterally. Suitable springs, v, back of the 5 plates near the heels thereof, as shown in Fig. 16 of the drawings, serve to hold the free ends of the plates o o to a certain degree normally outward from the sides of the die L.

On the main shaft B is rigidly mounted a 10 roller, W, arranged in position to be traversed by the free end of the oscillatory arm K, and of a diameter to cause it to impinge the shoe held on the former M. Said roller is provided with beveled projecting flanges or cheeks 15 v, which are fixed in such relative positions as to cause them to compress the side plates, O, of the former-arm K.

The operation of bending and completing the shoe after the blank has passed through 20 the creasing and swaging process, as hereinbefore described, is as follows: In the descent of the arm K the protruding former encounters the center of the bar lying in the guide-channel a, and as the said former passes through 25 the excision of the lower plate, b, the ends of said excision press the bar around the former M, the jaws N N being in the meantime forced back from the face of the former-arm by the bearing of the edge of the upper plate, b', 30 against the face of the said jaws. After the former-arm K has passed beneath the plate b the rollers 8 8 further bend the blank around the former, as hereinbefore described, and then the jaws N N automatically assume their 35 normal projecting position, and thus embrace the sides of the shoe hanging on the former. The former-arm K next encounters the roller W, and in traversing the same the peripheral face of the roller presses onto the face of the 40 shoe, and at the same time the cheeks v of the roller press the side plates, O O, of the arm K against the sides of the jaws N N, and the latter against the sides of the shoe still adhering to the former M, thus compressing the 45 shoe and subjecting it to a second swaging process, giving it an even contour and finishing the shoe.

The feed mechanism by which the heated bar is conveyed to the before-described shoe-forming machine consists of two horizontal disks or rollers, R' R', mounted on vertical arbors 1, which are journaled in suitable boxes or bearings on a pedestal, 2, said rolls being rotated synchronously, and in opposite directions 50 by pinions 3 of equal dimensions fastened to the respective arbors. A miter-gear, 4, is attached to the end of the main shaft B and engages a miter-gear, 5, loosely mounted on one of the arbors 1. A clutch, 6, slides on a feathered portion of the aforesaid arbor, and is adapted to interlock with the hub of the loosely-mounted miter-gear 5, which receives a continuous motion from the main shaft B. By means of a lever, 7, pivoted on the pedestal 2, and connected at one end with the clutch 6, and having the opposite end in a position to be conveniently manipulated by the operator,

the clutch can be thrown in and out of connection with the miter-gear 5, and thus the feed-rolls R' can be set in motion or stopped 70 at will by the operator. The feed-rolls have each two peripheral flanges, between which is guided the bar to be fed to the machine. The lower flanges are maintained intact, and the periphery of the upper portion of the rolls is 75 mutilated, leaving only a segmental portion to grip the bar to be fed to the machine, the mutilated portion, losing its hold on the bar, produces an intermittent feed-motion, the intervals in the feed corresponding to the time 80 required to crease and swage the portion of the bar entering into the machine. I do not, however, wish to be confined to the precise form or construction of the face of the feed-rolls to impart the intermittent movement to 85 the bar from which the shoe is to be formed, inasmuch as the feed-rolls may be arranged to receive an intermittent instead of a constant rotation.

Having described my invention, what I claim 90 as new, and desire to secure by Letters Patent, is—

1. In combination with the creaser C, slide S, and presser D D' on said slide, the vertical levers P P, pivoted on the frame A, the push-bars k k, interposed between the upper end of the levers P P and slide S, the tractile spring m, for drawing the slide toward the levers, and the rotary cams Q Q, having abruptly-terminating eccentric contours for imparting quick 100 action to the levers P P, substantially as set forth and shown.

2. In combination with the creaser C, slide S, and a presser, D D', on said slide, the levers P P, pivoted on the sides of the frame, 105 push-bars k k, interposed between the upper ends of the levers and the slide, spring m for retracting the slide, the rotary cams Q Q, engaging the lower end of the levers at one side, the elbow-levers R R, arranged at the opposite side of the levers P P, the push-bars n' n', interposed between the arms of the levers R R and levers P P, and the springs n n actuating the levers R R, substantially as described and shown.

3. In combination with the creaser and the reciprocating slide and presser, a rock-shaft mounted on the frame over the creaser, jaws projecting from the rock-shaft, and an oscillatory swaging-arm suspended from said jaws, 120 substantially as and for the purpose specified.

4. In combination with the shoe-bending mechanism and creaser, the slide S, plate E, provided with the guide-groove a, and the pressing-plate D, hinged on plate E, and having the overhanging face D' occupying the side of the groove opposite the creaser, substantially as and for the purpose specified.

5. In combination with the creaser C and slide S, the hinged plate D and the face D', 130 detachably connected to said plate, substantially as described and shown, for the purpose set forth.

6. In combination with the creaser C and

its sustaining-holder *f*, provided with flanges *f'*, the dog *h*, removably attached to the frame and holding by its free end the creaser and its holder in their positions, substantially as described and shown.

7. The combination, with the creaser *C*, of a supporting-holder, *f*, resting with its front portion on a rocker-bearing, the dog *h*, holding the shoe on its said bearing, and set-screws *e*, for adjusting said holder in its position, substantially as described, for the purpose specified.

8. In combination with the creaser and presser, a rock-shaft arranged above the creaser, a swage suspended from the rock-shaft, and a lever connected with the swage to carry it out of its operative position when required.

9. In combination, with the slide *S* the plate *E*, provided with the groove *a*, and the lining *a'*, detachably secured in said groove, as shown and described.

10. In combination with the oscillatory arm carrying the die and former for bending

the shoe, a rotary die having projecting cheeks adapted to receive between them the shoe-carrying end of the arm and laterally compress the shoe, as specified.

11. The combination of the oscillatory arm carrying the die and former for bending the shoe, laterally yielding plates on opposite sides of the arm, movable jaws interposed between the plates and die, and a rotary die having projecting cheeks adapted to embrace the end of the oscillatory arm and compress the side plates thereof, substantially as described and shown, for the purpose set forth.

In testimony whereof I have hereunto signed my name and affixed my seal, in the presence of two attesting witnesses, at Syracuse, in the county of Onondaga, in the State of New York, this 12th day of February, 1884.
